(57) CLAIM

The ornamental design for a lampshade of a street lamp, as shown and described.

DESCRIPTION

FIG. 1 is a perspective view of a lampshade of a street lamp showing the new design;

FIG. 2 is a front view thereof;

FIG. 3 is a rear view thereof;

FIG. 4 is a right side view thereof, the left side view being a mirror image of the right side view;

FIG. 5 is a top view thereof;

FIG. 6 is a bottom view thereof;

FIG. 7 is another perspective view thereof; and

FIG. 8 is a perspective reference view of the lampshade of a street lamp in use; and,

FIG. 9 is another perspective reference view of the lampshade of a street lamp in use.

The broken lines shown on the drawings depict environment only and form no part of the claimed design.
